ALBERT G. WETMORE, OF PLYMOUTH, INDIANA.

BOX AND PROCESS OF AND APPARATUS FOR THE MANUFACTURE THEREOF.

1,394,593.

Specification of Letters Patent. Patented Oct. 25, 1921.

Application filed April 9, 1919. Serial No. 288,825.

To all whom it may concern:

Be it known that I, ALBERT G. WETMORE, a citizen of the United States of America, and a resident of Plymouth, Indiana, have 5 invented a certain new and useful Improvement in Boxes and Processes of and Apparatus for the Manufacture Thereof, of which the following is a specification.

This invention relates to the manufacture 10 of boxes in general, but more particularly to those which are reinforced with wire, and which are formed from side wall sections having cleats formed to engage each other at their ends, together with heads or end 15 walls that are secured to the cleats to form the ends of the box.

Generally stated, the object of the invention is to provide an improved method or process whereby the blanks which are employed in making boxes of this character can be first formed in one stiff section composed of a sheet of veneer or other material having the cleats secured thereto, and whereby the blank, thus partially formed, can then be 25 divided into sections, by cutting the cleats and severing the sheet transversely along a line opposite the cuts, leaving the sections of the blank connected together by wires or other flexible means, and with the severed 30 edges of the sheet adapted to engage each other to provide tight corners for the box.

Another object of the invention is to provide a novel and efficient machine for thus cutting the cleats, and for severing the sheet 35 material transversely of the blank in the manner above stated, thereby to convert the partially formed or stiff blanks into flexible blanks which can be bent around the heads or end walls of the box.

40 Another object is to obviate the necessity of using certain methods and features of construction heretofore considered necessary or desirable in the manufacture of wire bound or similar boxes.

45 It is also an object to provide certain details and features of construction and combinations tending to increase the general efficiency and the desirability of a box of this particular construction, and of a machine of 50 this particular character.

To these and other useful ends the invention consists in matters hereinafter set forth and claimed.

In the accompanying drawings—

Figure 1 is a side elevation of a box blank 55 cutting machine embodying the principles of the invention.

Fig. 2 is an end elevation of said machine.

Fig. 3 is a detail view showing the manner in which the saws cut the V-shaped notches 60 in the cleats of the blank.

Fig. 4 is an enlarged detail sectional view, showing the saws and cutters and work-carrying belt in side elevation, and showing the structure for supporting the saws in vertical section. 65

Fig. 5 is an enlarged detail view showing the manner in which the two saws co-operate to successively cut first one side and then the other side of a V-shaped notch in the 70 cleat, so that the notch is not complete until after the second saw passes through the cleat, and whereby a groove is cut in the sheet of veneer or other sheet material, in line with the apex of the V-shaped notch, 75 thus forming a line along which the sheet is subsequently severed.

Fig. 6 is a similar view, showing the manner in which the cutter severs the sheet along the bottom of the groove previously formed 80 by the two saws.

Fig. 7 is a perspective of the partially formed or stiff blank, showing the construction and appearance of the same before it is passed through the machine. 85

Fig. 8 is a similar view showing the construction and appearance of the blank after passing through the machine.

Fig. 9 is a perspective of one end portion of the separate or loose section which, for 90 the particular form of box shown and described, forms the cover or top wall thereof.

Fig. 10 is a perspective of the complete blank flexed into position to receive the heads or end walls of the box. 95

Fig. 11 is a perspective of one of said heads or end walls, with one edge portion thereof shown broken away for convenience of illustration.

Fig. 12 is an enlarged detail view showing 100 a feature of construction of the box.

Fig. 13 is a detail fragmentary view showing another method of cutting the cleats without grooving the veneer.

Fig. 14 is a detail view showing the form 105 of rotary cutter to be used when the veneer

is not grooved by the saws and when the rotary cutter is required to perform the entire work of cutting a V-shaped groove in the veneer, with the apex of the groove 5 extending through to the outer surface of the blank.

As thus illustrated, the machine comprises a suitable body frame 1 adapted to support the various operative parts in suitably elevated position. An endless traveling work-holder 2, composed of sprocket chains suitably mounted on sprocket wheels 3 at the opposite ends of the bed or table 4 which forms the top of the body frame, is employed for carrying or propelling the blanks along sidewise, the work-holder being provided with suitable projections or pushers 5 for this purpose, so that the blanks are carried forward in a manner that will be readily understood, the endless sprocket chain work-holder thus formed being supported to slide on the said table, in any suitable or desired manner, so that it will not sag under the weight of the blanks, nor be depressed by the action of the saws and cutters, as will hereinafter more fully appear. Any suitable means can be employed for operating said endless traveling work-holder or carrier, so that the blanks will be propelled or carried forward at the proper speed.

Transversely arranged beams 6 and 7 are disposed a suitable distance above the work-holder, and supported by side frames 8, 35 through the medium of screws 9 which can be adjusted by rotation of the crank shafts 10 which have bevel gears 11 to engage the bevel gears 12 on the upper ends of said screws, said shaft being mounted in bearings 13 on the side frames 8, and having a crank handle 14 for the operation thereof, whereby the beams 6 and 7, which are disposed a suitable distance apart, but preferably in the same horizontal plane, can be 45 raised and lowered to suit the requirements. The beam 6 is formed to provide a guideway for the sliding supports 15 and 16, at opposite sides thereof, and is formed with a rack 17 at each side thereof to engage the pinions 50 18 carried by the supports 15 and 16, and by means of handles 19 these pinions are rotated in engagement with the racks to cause the supports 15 and 16 to slide along the beam 6, for a purpose which will hereinafter more 55 fully appear. It will be understood that the rack and pinion arrangement shown in Fig. 2 is duplicated on the other side of the beam 6, and on both sides of the beam 7, whereby there are four racks and four 60 pinions. An inclined shaft 20 is mounted on the support 15, and a similar shaft 21, disposed at the opposite angle, is mounted on the support 16, whereby these two shafts are arranged, one in front and one behind

the transverse beam 6, and the lower ends of these shafts are provided with rotary saws 22 and 23 to form the V-shaped notches in the cleats, it being observed that the two saws converge to a longitudinal line disposed immediately over one of the sprocket 70 chains of the traveling work-holder.

It will be seen that the beam 7 is similarly equipped with a pair of saws 24 and 25, which are mounted and operated exactly like those previously described, whereby a V-shaped notch is cut in each cleat directly over another link belt or sprocket chain of the endless traveling work-holder, as shown more clearly in Fig. 2. With this arrangement, the said saws can be adjusted laterally 80 for blanks of different lengths, and the sprocket chains of the work-holder are also adjustable laterally on the shafts 26, in any suitable or well known manner, whereby the entire machine is adjustable for the purpose 85 of making blanks of different lengths. The said saws may, of course, be driven by belts applied to the pulleys 27 on their shafts, or in any other suitable or desired manner. Preferably, the saws are so adjusted or set 90 relatively to each other, that they not only form the V-shaped notches of the cleats, but also cut V-shaped grooves in the sheet of veneer, or other sheet material, to which the long cleats are secured. The arrangement 95 of the saws in pairs in this manner, and with one pair in advance of the other, is of advantage, it will be seen, as in this way the notches in the cleats can be quite close together, if necessary, whereas with the saws 100 all mounted on the same transverse beam, or all in line transversely of the machine, there would necessarily be a limit to the shortening of the distance between the notches, so that the blanks of less than a certain length 105 could not be made; but, with the construction and arrangement shown and described, blanks of any length, within limits, and with the notches quite close together or farther apart, can be made on one and the same 110 machine.

After the notches are thus formed in the long cleats A of the partially formed or stiff blank, so that V-shaped notches B are formed in the blank, as shown in Figs. 115 7 and 8, and after the grooves C are formed in the sheet of veneer, which grooves preferably extend parallel with the grain of the wood, of course, the partially separated sections of the sheet are then entirely separated from each other by the rotary cutters 28 which are mounted on a shaft 29 behind the saw 25, each cutter consisting of a disk having a sharp edge which will make a thin cut entirely through the sheet without cutting away any of the material thereof, thus leaving the two severed edges of the sheet beveled in the manner 120 125

shown. These rotary cutters are raised and lowered by bevel gear mechanism 30, through the medium of vertically disposed screws 31 that support the boxes or bearings 32 of the 5 shaft 29, so that by rotation of the shaft 33 of said mechanism the cutters can be adjusted up and down in unison, thereby to accurately position their cutting edges in order to cause them to cut through the sheet in the 10 desired manner. It will be seen that these rotary cutters 28 are also directly in line with some of the link belts or sprocket chains of the endless traveling work-holder, so that the veneer or other sheet material is solidly 15 supported below the edges of the rotary knives or cutters thus provided, and whereby a very thin and clean cut will be made through the portion of the sheet remaining after the cutting of the groove therein by the 20 saws. If desired, and with a view to avoiding any injury to the binding wires of the blank, the said wires can be depressed or slightly bent away from the blank, or formed at some stage of the process with kinks at 25 the points where the box side sections meet, as shown at 34 in Fig. 12, and the work-holder may be formed accordingly to receive these bent portions of the binding wires. These kinks 34, of course, tend to draw the 30 sections more tightly together at the corners of the box, at some stage of the process, as the kinking or looping of the wire in this way tends to shorten the connection between the sections. The cutters 28 have sharp 35 edges, of course, but by this is simply meant that the edges are sharp enough to sever the sheet by the making of a thin and clean cut, without cutting away any of the material of the sheet, so that the two severed edges will 40 not only be beveled, but will also remain in engagement with each other, or very nearly so, thereby to provide a tight joint between the two edges at the corner of a box when the two sections of the sheet are folded relatively to each other in the manner shown. 45 Thus the V-shaped notches and grooves are formed first, and then the rotary cutters 28 roll along in these grooves and complete the operation by totally severing the sheet along 50 transverse lines, with the result that the partially formed or stiff blank is thereby reduced to a flexible blank which can be folded around the heads or end walls D of the box.

Spring guards 35, of any suitable character, 55 can be employed for holding the blanks down while passing under the saws, and similar or any suitable spring guards 36 can be provided for doing the same thing while the blanks are passing under the rotary cutters 28, thus preventing the blanks from rising and falling while being operated upon by the saws and cutters.

If desired, the end of the shaft 29 can be 60 provided with a belt pulley 37, so that the rotary cutters can be positively driven, thereby to facilitate the cutting action.

As shown in Figs. 7 to 11 inclusive, the construction is of a knock-down character, the cleats being provided with grooves 38 to receive the tongues or ridges 39 formed on the cleats 40 which are secured to the outer sides of the heads or end walls D, in position to thus interlock with the cleats of the blank, thereby holding the heads or end walls in place without the insertion of any fastening devices. It will be understood, however, that ordinary heads or end walls, stapled to the cleats of the blank, in the ordinary or well known manner, can be employed, if such is desired or necessary. Also, as shown, the blank comprises only three sections, which are flexibly connected together by the binding wires 41, in the well known manner, and a separate section E is provided to form the cover or top wall of the box, this cover having binding wires 42 which have their ends formed with portions 43 to engage the loops 44 on the ends of the wires 41, whereby the cover can be tightly secured in place, the end portions of the wires being twisted or tightened in any suitable or well known manner. It is obvious though, that the invention is not limited to any particular form of box or crate, or to the making of blanks having any particular number of sections. 95 The machine may have as many saws as are necessary to form the desired number of notches in the box blank, depending upon the shape of the box to be made and the number of sections required for the blank, 100 and the rotary knives or cutters which sever the sheet can be arranged accordingly, and can be of any desired number.

By beveling the edges of the sheets, as shown, the two edges themselves are adapted 105 to be brought together, to form a tight joint along the corner of the box when the blank is folded, and the overlapping of one sheet by the other is not necessary, inasmuch as the bevel forms a tight joint between the 110 two adjacent edges themselves, so that a lap joint is not necessary. In this way, therefore, the edge of each sheet is held by the other sheet against displacement inwardly, by pressure on the outside for each sheet 115 opposes the inward flexing of the other. The saws, of course, can be set at any desired angles, so that the two sides of the V-shaped notch will be at right angles to each other, as shown, or at either an acute or an obtuse 120 angle, if such is necessary or desirable, which is one advantage of the V-notch construction shown and described, as distinguished from other formations by which the ends of the cleats have heretofore been brought together. 125

The cover section E can, of course, be constructed in any suitable or desired manner, by any suitable machinery, so that its

cleats and edges will properly engage the cleats and edges of the front and back wall sections. It is also obvious that the cleats and wires can be secured to the veneer or 5 other sheet material by staples, in the ordinary manner, and by any suitable machinery, thereby to produce the partially formed or stiff blanks. Thereafter the blanks are passed through the machine shown and 10 scribed, in the manner explained, thereby to divide the long cleats into as many short cleats as is necessary in order to produce blanks of the required length, or having the desired number of flexibly connected 15 sections.

The notches B, as previously described, extend, when finished, entirely through the cleats, and into the veneer. Obviously, however, notches can be cut which extend either 20 entirely through the cleats, without extending into the veneer, if such is necessary or desirable. As shown in Fig. 13, the notch F extends entirely through the long cleat, but not into the veneer. The saws 22, 23, 25 24, and 25 can be set, of course, by adjusting them in the manner described, so that notches or openings or V-shaped cuts will be made in the cleats, either as shown in Fig. 8 and Fig. 12, or as shown in Fig. 13, depending 30 somewhat upon the character of the veneer or wood or other sheet material employed and the quality and thickness thereof. If the notches or V-shaped cuts are made as shown in Fig. 13, then the V-shaped groove 35 is cut in the veneer by a cutter G, as shown in Fig. 14, and its edge is provided with a double bevel exactly in alinement with the two sides of the notch F, so that the V-shaped groove thus cut in the veneer will 40 extend through to the outer surface of the blank, along a sharp line that will show on the under side of the veneer, which is the outer side when the blank is folded. In such case, these cutters G, which are the same 45 as the cutters 28, but perhaps a little thicker, will be rapidly rotated to actually cut away some of the sheet material, thereby to form the V-shaped groove in the veneer. With this adjustment of the machine, the cleats 50 are subdivided by one step, without scoring or cutting the veneer, and the separation of the veneer into sections is then accomplished by another step in the process or method, by the rapidly rotating cutters G, so that the 55 blank becomes flexible, as previously described. When the machine is set or adjusted to operate as shown in Figs. 5, 6 and 12, the saws make a preliminary groove in the veneer, as explained, and the cutters 60 28 then merely slit the bottom of such groove, and in this case the cutters 28 of hardened tool steel, for example, can be adjusted to roll on the tops of the link belts, the latter having flat surfaces for this purpose, or even

being provided with a slight groove for the 65 edge of the cutter 28, so that the latter will just cut through the veneer, thereby to form the thin and clean and straight line of division or separation on the outer side of the blank, and in such case the cutter 28 will 70 not cut away any of the sheet material, or is not required to do this. In Fig. 13, however, the operation will probably require an actual cutting away of some of the sheet material, depending somewhat upon the 75 thickness and quality of the sheet material. In either case, however, the sheet material is preferably held down perfectly flat by the presser feet 35 and 36 at each side of the saws, and at each side of the rotary cutters, 80 so that if the material is warped or uneven it will not be improperly cut—that is to say, such warping will not interfere with the cutting of a clean and straight groove of uniform depth and width in the veneer, and 85 will not interfere with the cutting or notching of the long cleats to divide the latter into as many sections as there are sections for the blank.

Thus it is obvious that the invention is not 90 limited to a box of any particular size or shape, or to a box having any particular number of sides, nor to the making of blanks having any particular number of sections, 95 as the number of sections will vary according to the shape of the box, the square or rectangular box shown being merely illustrative of one form of the invention. As shown, the box blank has the cleats secured to its inner surface and the binding wires to the outer 100 surface thereof. Also it will be seen that the invention is not limited to any particular adjustment of the saws, inasmuch as they can be adjusted to merely cut through the 105 cleats, without cutting into the veneer, or may be adjusted to cut through the cleats and into the veneer, thus forming a preliminary groove to receive the rotary cutter; and, while the saws are shown in staggered 110 relation to each other, so that one side of the V-shaped cut is made first, and the other side afterward, it is obvious that both sides of the cut can be made simultaneously by suitable arrangement of the saws, should this method 115 be preferred to the other method or process which involves the formation of one side of the cut first and the other side afterward. By V-shaped notches, it will be understood 120 is meant a cut which extends either entirely through the blank, or a cut which extends only partially through the blank, or through the cleats, for the notching of the inner side of the blank to make it foldable may be done in various ways, and the ultimate severing 125 of the sheet material to form sections which are entirely separate and which are only connected together by the wires or other flexible members, can be accomplished in the man-

ner shown and described, or by any suitable method or machinery.

What I claim as my invention is:—

1. A machine for cutting the cleats and sheet material of a partially formed box blank to divide the blank into flexibly connected sections, comprising instrumentalities for entirely severing the cleats on a line extending across the blank, thereby forming oppositely disposed notches therein, leaving the sections of the cleats still connected end to end by the sheet material, a structure for supporting the blank during the operation, and cutting means disposed in position for severing the sheet material along said line, leaving the sections united merely by the flexible connection between them.
2. A structure as specified in claim 1, said cutting means including a cutter having its edge formed to make a thin straight cut through the sheet without cutting away any of the material thereof.
3. A structure as specified in claim 1, said cutting means including a cutting disk disposed in position to engage the inner surface of the blank and formed with a sharp edge adapted to make a thin straight cut through the sheet without cutting away any of the material thereof.
4. A structure as specified in claim 1, said instrumentalities being adapted to cut a groove in the sheet to form the line for said cutting means.

5. A structure as specified in claim 1, said instrumentalities including a saw disposed at an angle to form one side of the notch, and another saw disposed at an angle to form the other side of the notch, the two saws being disposed one ahead of the other to operate successively on the cleat, so that V-shaped notches are successively cut in the cleats on said line.

6. A structure as specified in claim 1, said instrumentalities being disposed in position to successively cut opposite notches in the cleats nearer one end of the blank, and thereafter to successively cut opposite notches in the cleats nearer the other end of the blank.

7. A structure as specified in claim 1, said structure comprising a traveling work-holder to propel the blanks along sidewise, so that the cleats extend transversely of the direction of travel, said instrumentalities being disposed in position to form a groove along said line and to form the notches in the cleats of the moving blank, and said cutting means being disposed in position to pass through the groove and notches thus previously cut by said instrumentalities.

8. A structure as specified in claim 1, said instrumentalities including saws arranged to form V-shaped notches in the cleats, and to cut a V-groove in the sheet

material, along said line on the inner surface of the blank, said structure comprising a traveling work-holder to carry the blanks along sidewise, so that the cleats extend transversely of the direction of travel, and said cutting means including a rotary disk having a sharp edge formed to traverse said groove and make a thin straight cut through the sheet without cutting away any of the material thereof.

9. The process of making a box blank, comprising the fastening of cleats and flexible binding members to the sheet material to form a stiff blank having said cleats on the inner surface of the blank and the binding members on the outer surface thereof, cutting notches in the cleats to completely sever and thereby divide each cleat into a plurality of sections, leaving the sections still connected by the sheet material and the flexible members, and completely severing the sheet material transversely in line with said notches; so that the sheet material is entirely divided after the cleats and binding members are secured thereto, finally leaving the sections of the blank connected merely by said flexible members.

10. A process as specified in claim 9, comprising the grooving of the sheet when the notches are cut in the cleats, thereby partially to sever the sheet, and thus forming grooves along which the complete severing is thereafter effected.

11. A process as specified in claim 9, comprising a V-formation of said notches, and a similar V-formation between the edges of the sheet, substantially as shown and described, prior to the complete separation of said edges.

12. A process as specified in claim 9, in which the severing of the sheet involves a cutting operation which is accomplished without cutting away any of the material of the sheet.

13. The process of making a box blank, comprising the securing of cleats to the sheet material to form a stiff blank, cutting notches in the cleats to completely sever and thereby divide each cleat into sections, leaving the sections still connected end to end by the sheet material and thereafter completely severing the sheet material transversely in line with said notches, so that the sheet material is entirely divided after the cleats are secured thereto.

14. A process as specified in claim 13, involving the grooving of the sheet to form a line for the final severing thereof.

15. A process as specified in claim 13, in which the severing of the sheet involves a cutting operation which is accomplished without cutting away any of the material of the sheet.

16. A process as specified in claim 13, in

which one side of the notch is made first, and the other side afterward, so that a V-notch is formed, and in which the sheet is grooved while the notches are being made, so that a groove is formed in line with the notches to partially sever the sheet, the final and complete severing being accomplished afterward along the bottom of the groove.

10 17. A structure as specified in claim 1, said instrumentalities being adjustable to cut through the cleats without cutting into the sheet material, if desired, or to cut through the cleats and partially through the sheet material, to form a groove along said line if the latter method is necessary or desirable.

18. The process of making a wire-bound box blank, comprising the fastening of wires to sheet material to form a stiff blank of the required length, and thereafter severing the sheet material entirely across the blank, without cutting said wires, to provide a plurality of separate sections which are disposed edgewise together and flexibly connected merely by said wires.

19. A process as specified in claim 18, including the fastening of cleats to the sheet material, and the severing of said cleats into sections before the sheet material is severed.

20. A process as specified in claim 18, including two successive cutting operations to accomplish the complete severing of the blank into sections, so that a notch is first cut in the blank and thereafter a cut is made entirely through the sheet material at the center of said notch.

21. A process as specified in claim 18, in-

cluding the step of forming a V-notch by cutting first one side thereof and then the other, thereby also at the same time and by this same step forming a V-groove in the sheet material, and thereafter cutting entirely through the sheet material along said groove.

22. A process as specified in claim 18, including the flexing of the wires to prevent them from being injured by the cutting means.

23. The process of making a wire bound box, comprising the stapling of wires to sheet material, using the same staples to also secure long cleats to the sheet material, thereby to form a long stiff blank of the desired length, cutting notches in said cleats at predetermined points between said staples, to divide each cleat into short sections, and also completely severing the sheet material in line with said points, leaving the sections of the blank flexibly connected merely by the wires previously stapled thereto.

24. The process specified in claim 23, in which the severing of the sheet material is preceded by the cutting of grooves along the lines predetermined for the severance of said material.

25. The process specified in claim 23, in which the notches are cut successively in each cleat, and the sheet material is grooved along the lines predetermined for the subsequent complete severing of said material.

26. The process specified in claim 23, in which the cutting of said notches precedes the complete severing of the sheet material.

ALBERT G. WETMORE.
